UNITED STATES PATENT OFFICE.

ERASmus L. KEYES, OF HOPEDALE, ILLINOIS.

SWEEPING-MACHINE.

SPECIFICATION forming part of Letters Patent No. 755,596, dated March 22, 1904.

Application filed September 21, 1903. Serial No. 174,090. (No model.)

To all whom it may concern:

Be it known that I, ERASmus L. KEYES, a citizen of the United States, and a resident of Hopedale, in the county of Tazewell and State 5 of Illinois, have made a certain new and useful Invention in Sweeping-Machines; and I declare the following to be a full, clear, and exact description of the same, such as will enable others skilled in the art to which it appertains 10 to make and use the invention, reference being had to the accompanying drawings, and to letters of reference marked thereon, which form a part of this specification.

Figure 1 is a perspective view of my sweeping-machine. Fig. 2 is a section on the line 15 2 2, Fig. 3. Fig. 3 is a section on the line 3 3, Fig. 2. Fig. 4 is a section on the line 4 4, Fig. 3.

This invention has relation to sweeping-machines for streets, lawns, &c., and has for its 20 object the provision of a simple and efficient machine for this purpose.

With this object in view the invention consists in the novel construction and combinations of parts, all as hereinafter described, and 25 pointed out in the appended claims.

Referring to the accompanying drawings, the letters A A designate the carrying-wheels, upon which is mounted the box-form frame B, 30 open at the bottom at b, transverse rotary brushes C C being mounted in the side walls of said frame and having their bristles projecting beyond said opening. Above and central of said brushes is arranged the transverse 35 shaft D, carrying the exhaust-fan D' at its middle portion.

E is a guard and division plate, of a single piece of sheet metal arched around the brushes and bent vertically upward centrally of the 40 box-form frame and around the fan-shaft, a metal casing d around the fan joining said plate E; this plate dividing the interior of frame B into a lower receptacle X for brushes, fan-shaft, and fan and an upper dirt-receptacle Z. At about the junction of the vertical and arched portions of the plate E extend 45 downward at each side the oppositely-inclined bottom boards F, forming the bottom of the dirt-receptacle Z, the fan-shaft casing d form-

ing a central vertical partition in said receptacle, from which lead off the inclined bottoms F.

The dirt-receptacle Z has a hinged door at front and rear at z z, such doors closing against the inclined boards F and each when opened allowing the discharge of the contents of one-half of the dirt-receptacle at that side of the partition. This receptacle is also provided with a hinged perforated cover z', of wire-cloth or the like, which when opened admits of access to the fan, the casing of which has a hinged 60 cover d' and is open rearwardly at d' for exit of air and dirt carried therewith into its receptacle.

Suitable gearing G connects the brush-shafts with the carrying-wheel shaft to drive the 65 brushes, a belt and pulleys g or the like connecting the fan-shaft with the carrying-wheel shaft at the opposite side of the machine.

In operation the dirt, grass, leaves, or the like are carried up between the rotary brushes 70 into the fan-shaft casing, thence into the fan-casing, and are discharged with the exhaust-air into the dirt-receptacle, the perforated cover z admitting of the escape of such air. In discharging the dirt the doors z are opened, 75 as before stated, effecting an automatic discharge.

Having thus described my invention, what I claim as new, and desire to secure by Letters Patent, is—

1. A sweeping-machine, comprising the box-form frame, the rotary transverse brushes therein, the transverse fan-shaft and fan above and central of said brushes, the guard and partition plate inclosing said brushes fan-shaft 85 and fan and dividing the box-form frame into upper and lower compartments, and partially dividing the upper dirt-compartment, front and rear inclined bottoms for the two halves of said dirt-compartment, and front and rear hinged doors for the same, substantially as specified.

2. A sweeping-machine, comprising the box-form frame, the rotary transverse brushes therein, the transverse fan-shaft and fan above 95 and central of said brushes, the guard and division plate inclosing said brushes fan-shaft and fan and dividing the box-form frame into

upper and lower compartments, and partially dividing the upper dirt-compartment, front and rear inclined bottoms for the two halves of said dirt-compartment, front and rear hinged 5 doors for the same, a perforated cover for the dirt-compartment, and the hinged cover for the fan-casing, substantially as specified.

In testimony whereof I affix my signature in presence of two witnesses.

ERASMUS L. KEYES.
